UNITED STATES PATENT OFFICE

THOMAS LLOYD, OF NEW YORK, N. Y.

DESIGN FOR A TOY PISTOL.

SPECIFICATION forming part of Design No. 12,811, dated March 14, 1882.

Application filed February 6, 1882. Term of patent 7 years.

To all whom it may concern:

Be it known that I, THOMAS LLOYD, of New York, in the county and State of New York, have invented a new and original Design for 5 a Toy Pistol, of which the following is a specification.

The drawing represents a side view of my new design for a toy pistol.

This invention relates to a new configuration or form for a toy pistol; and it consists in making the same in form of an animal, so that the stock or handle part of the pistol will be formed by the tail of the animal, and the hammer and rest for exploding the fulminate by 15 the paws or feet of the animal.

In the drawing, A represents the body of the toy pistol. The same is in the form of an animal, the tail B of which is so curled as to form the handle of the pistol. One of the front legs 20 C, is directly beneath the other front leg, D, which can be actuated by the trigger E for exploding the fulminate that rests on C. The dotted lines show the position of the hammer D at the time of explosion.

I claim—

25

1. The design for a toy pistol, the same consisting of a body, A, in form of an animal, and the tail B, which constitutes the handle of said toy pistol, substantially as shown.

2. The design for a toy pistol, the same being in form of an animal with the front foot D above the other front foot, C, substantially 30 as shown.

3. The design for a toy pistol, the same being in form of an animal with the foot D above 35 the other foot, C, the tail B serving as a handle, substantially as shown.

This specification of my invention signed by me this 30th day of January, 1882.

THOMAS LLOYD.
